ELECTRIC LIGHT BULB

Walter K. Venema, La Grange, Ill., assignor to Sears, Roebuck and Co., Chicago, Ill., a corporation of New York

Filed Nov. 4, 1969, Ser. No. 19,944

Term of patent 14 years

Int. Cl. D26—01

U.S. Cl. D26—8

Fig. 1.

Fig. 2.

FIG. 1 is an elevational view of an electric light bulb embodying my new design, and

FIG. 2 is a top plan view thereof.

The characteristic feature of my design resides in the specific configuration of the lamp envelope.

I claim:

The ornamental design for an electric light bulb, as shown and described.
